FIREPLACE OR SIMILAR ARTICLE

Fred L. Toerge, Stamford, Conn., and Patrick H. O'Farrell, New York, N.Y., assignors to Trageser Copper Works, Inc., Jamaica, N.Y., a corporation of New York

Filed Jan. 5, 1967, Ser. No. 5,318

Term of patent 14 years

(Cl. D81—7)

FIG. 1

FIG. 1 is a perspective view of a fireplace showing our new design;

FIG. 2 is a bottom plan view thereof;

FIG. 3 is a side view in elevation thereof, both sides having the same appearance; and

FIG. 4 is a rear view of said fireplace.

The dominant features of the design are shown in full lines.

We claim:

The ornamental design for a fireplace or similar article, substantially as shown and described.
